UNITED STATES PATENT OFFICE.

CHARLES F. SMITH, OF BRIDGEPORT, CONNECTICUT, ASSIGNOR TO CONTINENTAL PAPER BAG COMPANY, A CORPORATION OF MAINE.

CUTTING MECHANISM.

No. 818,713.

Specification of Letters Patent.

Patented April 24, 1906.

Application filed April 1, 1905. Serial No. 253,347.

To all whom it may concern:

Be it known that I, CHARLES F. SMITH, a citizen of the United States, residing at Bridgeport, in the county of Fairfield and State of Connecticut, have invented certain new and useful Improvements in Cutting Mechanism, of which the following is a specification.

This invention relates to cutting mechanism, particularly to that class of such mechanism as is employed for severing a continuous web of paper into blanks or sections of uniform and predetermined length.

In the drawings accompanying this specification is illustrated a machine embodying one form and which may be the preferred form of my invention, and wherein—

Figure 1 is a plan view thereof. Fig. 2 is a side elevation corresponding with Fig. 1 and with side frame 2 omitted to better show those parts which would otherwise be obscured. Fig. 3 is a plan view of float F, and Fig. 4 is a detailed view of the cutting-blades.

My invention is peculiarly applicable in connection with paper-bag machines in which it is desired to sever a continuous paper tube into lengths suitable for bag-blanks. Such paper tubing may be a simple flat tube, or said tube may be provided with an inwardly-folded tuck in each side thereof.

My improved mechanism is also adapted for severing continuous webs, tubular or otherwise, having other forms of cross-section, or for severing flat continuous single, double, or multiple ply webs and all of the plies of which may pass above the float or a part above and a part below.

It is particularly desirable in severing paper tubing into bag-blank sections to provide at the forward end thereof a difference in length of the upper and lower plies, so that one ply may be gripped by the bag-bottom-forming mechanism without involving the other ply. Preferably the upper ply of the tubular blank is cut back, whereby the lower ply is allowed to project in front thereof. This provides at the other end of the blank, and which other end is later the mouth of the finished bag, a rearwardly-extending lip on the upper ply, whereby the bag-mouth may be conveniently opened for use. My improved machine provides for the severing of paper tubing and for the formation in sever-

ing on the ends of each section thereof of projecting portions, as described.

The machine illustrated in the drawings comprises side frames 2 3, in which may be supported the various parts of the mechanism. These side frames may be secured in suitable relation to each other by tie-frames 4 5, extending therebetween and fastened at their ends, respectively, to said side frames by bolts, as 6.

At F in the left-hand or entering end of the machine is shown the delivery end of some suitable tube-forming mechanism. This member F is in the nature of a float and is of suitable width to pass through an opening between feed-rolls 7 8. This opening is formed by oppositely-disposed reduced portions 9 in said rolls. Float F lies within and is surrounded by the paper tube which it is desired to sever. If said tube is provided with inwardly-folded tucks, said tucks are preferably disposed below the float.

My improved machine is provided with two pairs of feed-rolls 7 8 and 11 12, respectively, and which two pairs of rolls are driven at the same surface speed from pulley 10 by means of suitable gearing. This gearing is as follows: Turning freely upon stud 13, which stud projects outwardly from frame 3, is driving-gear 14. Pulley 10 is fast to said gear and turns with it about stud 13. Rolls 7 8 are supported for revolution upon shafts 15 16, respectively, and which shafts are provided with suitable bearings in brackets 18 19, upstanding from frames 2 3, respectively. Shafts 15 16 are provided with intermeshing gears 21 22, respectively, and lower gear 22 is engaged by driving-gear 14.

Upstanding and inreaching from frame 3 is bracket 17, and in which bracket are formed bearings for three shafts. One of these three shafts has fixed on its outboard end gear 23, meshing on the one side with driving-gear 14 and on the other side with idle gear 24 on stud 26. Feed-rolls 11 12 are mounted for revolution on shafts 27 28, respectively, and which shafts are provided with suitable bearings in brackets 30 31, upstanding from frames 2 3, respectively. Shafts 27 28 are provided with intermeshing gears 33 34, respectively, the lower one 34 of which meshes with idle gear 24. By the train of gears just described the two sets of feed-rolls 7 8 and 11 12, respectively, may

be driven to feed the web of paper in the direction of arrow A.

On the inboard end of shaft 20 and located about midway of side frames 2 3 is roll 25. Said roll is keyed to said shaft and turns therewith as driven by gear 23 on the outboard end of said shaft 20. In one side of said roll, reaching inwardly from the periphery thereof and located, preferably, oblique to the radius at its mouth, is a slot 29 for convenience throughout the length of said roll and in the present instance parallel to the axis thereof. In said slot is secured knife 32, having a serrated edge 35 projecting slightly above the periphery of the roll. The teeth 47 of said serrated edge are preferably V-shaped, but may be of any other suitable profile. The forward end 40 of float F is supported by said roll and is provided with a series of contiguous slots or grooves 36, through which the teeth 47 of serrated edge 35 of blade 32 sweep in their revolution about shaft 20. Said grooves lie lengthwise of float F, and the series extends entirely across said float. These grooves are spaced the same distance apart as the teeth of blade 32, so that during the time of coaction of float F and blade 32 each slot has a tooth in engagement therewith, whereby a continuous cutting-line is maintained across the whole width of float F. Said slots or grooves 36 approximately conform in profile of cross-section to the profile of teeth 47 and in profile of longitudinal section approximately to the arc described by said teeth during their engagement with said slots. Preferably said slots conform in profile of longitudinal section to an arc of a circle having a slightly-greater radius than that of teeth 47, whereby in operation said teeth do not commence to cut the paper until after those teeth have entered said grooves a short distance, whereby said cutting is performed gradually, or said grooves may be of greater length, if desired. Above float F a distance equal to the distance of shaft 20 below said float is shaft 50. Said shaft 50 has mounted thereon carrier 37 for blade 38. Said carrier is preferably adjustably secured to said shaft, as by clamp-screws 39. Blade 38 may be secured to carrier 37 by any suitable means, such as screws 41. Said blade may be a flat plate similar to blade 32; but in the present instance said blade 38 is illustrated as having a transverse profile curved rearwardly toward the middle thereof, and the seat therefor on carrier 37 is curved to correspond. Blade 38 is also provided with a serrated edge 42, whose teeth 43 are of the same character as teeth 47 of blade 32 and are spaced for engagement with grooves 46 in the upper side of float F as teeth 47 of blade 32 engage with grooves 36 on the under side of said float. Also grooves 46 are of the same character as grooves 36.

Roll-shaft 20 also has fixed thereto gear 44, 65 meshing with equal gear 45 on roll-shaft 50, whereby blades 32 38 are caused to rotate at the same speed. Also shafts 20 50 are preferably located out of one vertical plane, so that grooves 36 46 will not cut into each other, and thereby unduly weaken float F. Gear 23 has a pitch radius somewhat less than the radius of the serrated edge 35 of blade 32 or than the equal radius of serrated edge 42 of blade 38, whereby said edges are caused to travel slightly faster than the surface speed of feed-rolls 7 8 or 11 12. Near shaft 50 and between it and roll 11 is roll 48, fixed to shaft 49, and which shaft is mounted for rotation in bracket 17. On the rearward end of shaft 49 is fixed gear 51, and which gear is driven from gear 24 through idle gear 52. Said gearing is so proportioned that roll 48 is driven at the same surface speed as rolls 7 8 and 11 12 and is provided to hold float F down in position for engagement with blade 32, or, if desired, carrier 37 may be in the form of a roll similar to roll 25, and in that case said carrier 37 would be efficient to hold float F down against any upward pressure of blade or knife 32. Roll 48 could thus be dispensed with, or knife 32 may be mounted in a carrier similar to carrier 37 and float F sustained in proper alinement by independent rolls or otherwise. In case it is desired to sever a continuous web traveling on the upper side only of float F said float may be in the nature of a permanent table and supported, for instance, as table 54 is supported.

On shaft 53 is supported table 54. Said table is bent downward at 55 to allow the advancing tubular web of paper to pass therover. Said table is mortised at 56 to allow roll 12 to project upwardly therethrough for coaction with roll 11.

Rolls 11 12 are provided with a take-up device for increasing the speed during a small increment of time of that portion of the tubular web of paper in advance of the portions thereof which have been acted upon by blades 32 38 and whereby if said blades have failed to wholly separate the web said take-up device will complete that separation. Said take-up device comprises a rib 57, extending across one of the rolls, as 11, and parallel with the axis thereof. Said rib projects beyond the periphery of said roll and engages with a complementary groove 58 in roll 12. Said rib and groove may be formed integral with the rolls, respectively, or for convenience may be fashioned in separate pieces and inserted in said rolls, as shown at 59 60, respectively.

The operation of my improved mechanism is as follows: Suitable paper tubing either with or without an inwardly-folded tuck in each side thereof being delivered around float F and into the grip of rolls 7 8, the machine is

started in the direction indicated by the arrow on pulley 10. If tucked tubing is used, said tubing may be fed into the machine with the tucks either above or below the float; but when my improved mechanism is used in connection with paper-bag machinery it is customary and desirable to feed the tucks under the float. The tubing is then fed forwardly about float F, as indicated by arrow A, until the revolution of blade 38 brings those teeth 43 nearest the opposite sides of said blade into contact with that ply of the paper tube above the float. These teeth thereupon force the paper under them down into those grooves 46 corresponding with the end teeth of blade 38. Said blade then continues its revolution in an anticlockwise direction, and said end teeth successfully perforate and fully sever the upper ply of the tube at its edges. Then working inwardly the successive teeth of blade 38 repeat the operation on successive portions of the upper ply of the paper tube until that upper ply is severed throughout the whole width thereof. Any downward pressure that may be exerted by blade 38 against the float is sustained by the periphery of roll 25, which roll is revolving with a surface speed equal or about equal to that of the paper. At about the time of the completion of the severance of the upper ply of the paper tube blade 32 passes into engagement with the lower ply or plies of said tube. Lower blade 32, as illustrated, has a cutting edge parallel with its axis of revolution whereby all of teeth 47 pass into action at the same time and successively perforate and sever the portions of the tube lying below float F. As the curvature of blade 38 is rearward toward the middle thereof, the upper ply of the paper tube has a similar rearwardly-reaching curved line of severance, while the lower ply thereof has a straight line of severance. The forward edge of the upper ply being thus cut back toward the middle portion thereof leaves the forward part of the lower ply exposed to be conveniently gripped without involving the upper ply. In most cases the successive operations of the upper and lower blades, respectively, will entirely sever the advanced section of paper tube from the main web thereof, and the operation of my improved machine be thereby completed at this point; but occasionally with certain kinds of paper if blades 32, 38 are not carefully adjusted one or both of the edges of the flat tube where said edges lie around the lateral edges, respectively, of float F will not be completely severed. In such cases as the partly-severed section is fed by rolls 11, 12 between tension members 57, 58 thereon, respectively, said paper-tube section will be momentarily drawn forward at an increased speed, due to the take-up action on the tube of said tension members. As the

main tube-section is rigidly held by rolls 7, 8, 65 this take-up action of members 57, 58 will result in the pulling apart of any filaments of paper left uncut by blades 32, 38, and thereby complete the operation of severing the paper tube. 70

Various profiles of severance of either the upper or lower plies of the paper tube may be had by forming one or both of blades 32, 38 to correspond with such desired profiles. Always, however, the severance-lines must at 75 least approximately meet at each side of the flat tube, so as not to leave an excessive amount of paper to be severed by the tension means. If it is desired to sever a continuous web passing over the upper face only of float F, knife 32 and roll 25 may be omitted. 80

I claim—

1. A float having a plurality of contiguous grooves lengthwise in one face thereof, said grooves being of a depth less than the thickness of the float, a rotatable blade above the float, said blade having a plurality of teeth for engagement with the grooves respectively, in the float, all combined and working together substantially as described. 85 90

2. The combination of a float having a plurality of grooves lengthwise in one face thereof, said grooves being of a depth less than the thickness of the float, a rotatable blade having its axis substantially at right angles to 95 the length of the float, said blade having teeth for engagement with each groove respectively of the float, all combined and operating together substantially as described.

3. A float having a plurality of contiguous grooves lengthwise in one face thereof, a rotatable blade above the float, said blade having a transverse profile other than a straight line, and having a plurality of teeth for engagement with the grooves respectively in 100 the float, all combined and working together substantially as described. 105

4. A float, having a plurality of contiguous grooves lengthwise in each side thereof, said grooves being of a depth less than the thickness of the float and sufficient in number to extend substantially the width of each side of said float, a rotatable blade above the float, said blade having a plurality of teeth for engagement with the grooves in the upper side of the float and a rotatable blade below the float, said blade having a plurality of teeth for engagement with the grooves in the lower side of the float, and means to maintain the float for engagement with said blades, all combined and operating together substantially as described. 115 120 125

5. A float having a plurality of contiguous grooves lengthwise in each side thereof, the grooves in one side of the float being so disposed as not to penetrate the grooves in the other side of the float, said grooves being sufficient in number to extend substantially the

- 4
- width of each side of said float, a rotatable blade above the float, said blade having teeth for engagement with each groove respectively in the upper side of the float and a rotatable blade below the float, said blade having teeth for engagement with each groove respectively in the lower side of the float, and means to maintain the float for engagement with said blades, all combined and operating together substantially as described.
5. The combination of a float having a plurality of contiguous grooves lengthwise in each side thereof, the grooves in one side of the float being so disposed as not to penetrate the grooves in the other side of the float, a rotatable roll above the float said roll having a plurality of teeth for engagement with the grooves in the upper side of the float, and a rotatable roll below the float said roll having 15 a plurality of teeth for engagement with the grooves in the lower side of the float, all combined and operating together substantially as described.
6. The combination of a float having a plurality of contiguous grooves lengthwise in each side thereof, the grooves in one side of the float being so disposed as not to penetrate the grooves in the other side of the float, a rotatable roll above the float said roll having a plurality of teeth for engagement with the grooves in the upper side of the float, and a rotatable roll below the float said roll having 20 a plurality of teeth for engagement with the grooves in the lower side of the float, all combined and operating together substantially as described.
7. The combination of a float having a series of lengthwise grooves crosswise in one face thereof, the adjacent edges of said grooves contacting with each other respectively on the face of the float, a rotatable blade having a cutting edge complementary 25 to the cross-section profile of the series of grooves, means for feeding paper lengthwise on the face of the float and means to rotate the blade at a cutting-edge speed in excess of the speed of the paper-feeding means all combined and operating together substantially as described.
8. The combination of a float having a plurality of contiguous V-grooves, lengthwise in one face thereof said grooves having a longitudinal profile conforming to the arc of a circle, a rotatable blade above the float, said blade having a plurality of teeth complementary to and for engagement with the grooves in the float the teeth of said blade having a 40 radius of rotation less than the radius of the longitudinal profile of the grooves all combined and operating together substantially as described.
9. The combination of a float having a plurality of grooves lengthwise in one face thereof, said grooves being of a depth less than the thickness of the float and of such cross-section profile and so spaced that adjoining grooves will contact with each other respectively on the face of the float, a rotatable blade above the float said blade having a plurality of teeth for engagement with the grooves respectively, in the float all combined and operating together substantially as 45 described.
10. The combination of a float having a plurality of grooves lengthwise in one face thereof, said grooves being of a depth less than the thickness of said float and of such
- width of each side of said float, a rotatable blade above the float, said blade having a cutting-profile complementary to the cross-section profile of the series of grooves whereby a continuous line of coaction is attained within the limits of the engagement of the grooves and the rotatable blade all combined and operating together substantially as described.
11. A float having a plurality of contiguous grooves lengthwise in each side thereof, a rotatable blade above the float, said blade having a plurality of teeth for engagement with the grooves in the upper side of the float, a rotatable blade below the float, said blade having a plurality of teeth for engagement with the grooves in the lower side of the float, means for feeding paper lengthwise on each side of the float, means for rotating the blades to cause the teeth thereof to travel 55 at a linear speed in excess of the speed of the paper-feeding means and means to maintain the float for engagement with the blades, all combined and operating together substantially as described.
12. A float having a plurality of contiguous grooves lengthwise in one face thereof, a rotatable blade above the float, said blade having a transverse profile other than a straight line and having a plurality of teeth 60 for engagement with the grooves respectively in the float, means for feeding paper lengthwise on the face of the float and means to rotate the blade to cause the teeth thereof to travel at a linear speed in excess of the speed of the paper-feeding means all combined and operating together substantially as described.
13. The combination of a float having a plurality of grooves lengthwise in one face thereof, a rotatable blade above the float, said blade having a plurality of teeth for engagement with the grooves respectively in the float, means for feeding the paper over the float to the blade and means for feeding the paper away from the blade at a speed 65 momentarily greater than that of the feed to the blade, all combined and operating together substantially as described.
14. The combination of a float having a plurality of grooves lengthwise therein, a rotatable blade above the float, said blade having a plurality of teeth for engagement with the grooves respectively, in the float, means for feeding paper lengthwise on the face of the float and means to rotate the blade at a cutting-edge speed in excess of the speed of the paper-feeding means, all combined and operating together substantially as described.
15. The combination of a float having a plurality of grooves lengthwise in one face 70 thereof, said grooves being of a depth less than the thickness of said float, a rotatable blade above the float, said blade having a

plurality of teeth for engagement with the
grooves respectively, in the float, means for
feeding paper lengthwise on the face of the
float and means to rotate the blade at a cut-
ting-edge speed in excess of the speed of the
paper-feeding means, all combined and oper-
ating together substantially as described.

Signed this 31st day of March, 1905, at
New York, N. Y., in the presence of two sub-
scribing witnesses.
